UNITED STATES PATENT OFFICE.

RICHARD HALE SMITH, OF SPRINGFIELD, MASSACHUSETTS.

DESIGN FOR A FONT OF PRINTING-TYPE.

SPECIFICATION forming part of Design No. 24,061, dated February 19, 1895.

Application filed January 3, 1895. Serial No. 533,772. Term of patent 7 years.

To all whom it may concern:

Be it known that I, RICHARD HALE SMITH, a citizen of the United States of America, residing in Springfield, in the county of Hampden and State of Massachusetts, have invented and produced a new and original Design for a Font of Printing-Type, of which the following is a full, clear, and exact description.

The design relates generally to the configuration of the numerals together with the dollar sign, the cent sign and certain corner and border ornamentation.

The especial object of my invention is to produce a series of figures, marks and ornaments, which while being clear, distinct and bold will have a tasty and harmonious appearance, free from a harsh outline or harsh termination of the outlines.

In the accompanying drawing forming a part hereof, I have shown each numeral from 1 to 0 inclusive, together with the dollar mark or sign, the cent sign, the fraction $\frac{1}{2}$ and suitable and harmonious ornamentation for corners and borders.

The leading features of my design consist in the heavy curved body portions with lighter connecting lines, the figures, &c., being

formed in curved lines having longer horizontal axes than is common, and with the outlines terminating in sharp but uniform curves and meeting at a point, while the lines that are commonly more nearly straight are formed in harmonious curves in whole or in part and terminate in the outlines, meeting in a point with rapid separation between the outer lines just before they come together, the final outer lines being curved as stated. It will be observed that the marks of ornamentation as well as the figures are characterized by the distinctive features above noted.

By such configuration I am enabled to produce such figures, signs and characters as will present a bold and prominent appearance, while all harsh lines and terminations are avoided.

Having therefore described my invention, what I claim is—

The design for a font of printing type substantially as shown and described.

RICHARD HALE SMITH.
